UNITED STATES PATENT OFFICE.

THOMAS W. WARD AND HORATIO W. LASH, OF SHEFFIELD, ENGLAND.

APPARATUS FOR BREAKING METAL.

SPECIFICATION forming part of Letters Patent No. 623,853, dated April 25, 1899.

Application filed February 16, 1898. Serial No. 670,573. (No model.)

To all whom it may concern:

Be it known that we, THOMAS WILLIAM WARD, iron merchant, residing at Fitzalan Chambers, and HORATIO WILLIAM LASH, draftsman, residing at Albion Works, Sheffield, in the county of York, England, subjects of the Queen of Great Britain and Ireland, have invented certain new and useful Improvements in Machines or Apparatus for 5 Breaking Steel and other Metal Rails, Billets, Tires, or other Like Articles, (for which we have applied for a patent in Great Britain, No. 27,480, dated November 23, 1897,) of which the following is a specification.

15 The object of this invention is to provide an improved apparatus by means of which metal rails, billets, tires, and other similar articles can be broken with great facility and rapidity. The apparatus comprises a bed-plate 20 provided with a strong projecting abutment to resist the pressure to which the articles while being broken are subjected. The abutment is provided with steel surfaces or projections, preferably of tapered form or wedge shape, 25 against which the article to be broken is caused to bear, the said surfaces or projections being preferably removably fitted to the abutment to permit of their renewal when required. These steel bearing surfaces or 30 projections are arranged at suitable distances apart, and at a convenient distance in front thereof between the projections is arranged a hydraulic ram, the plunger of which carries a similar steel tapered projection, between 35 which projection and the projections on the abutment the article or portion of the article to be broken is placed, so that when the ram-plunger is forced out of the cylinder the pressure of the steel projection thereon, acting on 40 the portion of the article situated between the two projections on the abutment, readily effects the breaking of the article at this part.

Our invention will be clearly understood by the following description, with reference 45 to the accompanying drawings, of which—

Figure 1 is a side elevation, Fig. 2 a plan, partly in section, and Fig. 3 an end view, of apparatus constructed and arranged according to our invention. Fig. 4 is a longitudinal 50 section of a convenient arrangement of valves for governing the admission and exit of fluid to and from the hydraulic ram.

On a strong cast-metal base A are formed a strong abutment or strong abutments A², provided with dovetail recesses a to receive 55 blocks of steel B, against which the article to be broken is caused to bear. Secured to the base A is a hydraulic ram C, which may be secured to the base-plate A by bolts passing through lugs formed on the cylinder of the 60 ram or by a strap c', as shown, or by any other suitable means, the rear end of the said cylinder being arranged to bear against a strong abutment A³, standing up from the base-plate A, to resist the force exerted on 65 the articles to be broken. The plunger C² of the ram is provided with a tapered or wedge-shaped block B², which operates on the articles to be broken at a point about midway between the blocks B, carried by the abutments A² on the base-plate. For the purpose 70 of this invention only a very short stroke of the ram-plunger C² to effect the breaking of the articles, and consequently only a short cylinder, is required, which will permit of tires 75 of railway-wheels of the smallest diameter and similar-shaped articles to be broken being placed in the most advantageous position in the apparatus to be acted on by the block B² on the plunger C² of the hydraulic ram. 80

When the article to be broken is placed in position between the block B² on the plunger and the blocks B projecting from the abutments A², water under pressure is admitted to the cylinder of the hydraulic ram, so as to 85 force the plunger outward until by the pressure of the block B² against the article the breaking of the said article is effected, whereupon the water is allowed to escape from behind the plunger C², which plunger is at the 90 same time forced inward by water-pressure admitted to the cylinder C by the passage k and acting on the annular surface c² on the said plunger. Another portion of the article is then moved into position to be broken, and the operations hereinbefore described are 95 repeated. D are antifriction-rollers to support and facilitate the movement of the articles into position to be broken.

In Figs. 1 and 2 we have shown a railway- 100 wheel tire b placed in position to be broken, the said tire encircling the hydraulic ram and being in a horizontal position.

The arrangement of valves employed for

regulating the supply of water to the ram consists of two valves E and F, Fig. 4, fitted to seats in separate chambers G and H in a valve-box I. The said valves are normally held to their seats by a spring or springs K, Figs. 1 and 2, bearing on spindles e f of the valves, projecting to outside the valve-box through suitable stuffing-boxes g. The said valves may be forced from their seats by means of a lever L, Fig. 1, pivoted at d beneath the valve-box, upon which lever on opposite sides of the pivot d bear extensions e² f² of the valve-spindles e f, which extensions project through stuffing-boxes g² in the bottom of the valve-box I. The chamber G, containing the valve E, is in constant communication by the pipe or passage G² with the high-pressure pump or water under pressure, while the chamber H, containing the valve F, communicates with the ram-cylinder. By moving the lever L in the direction of the arrow in Fig. 1 the valve E in the chamber G is raised from its seat, whereupon water under pressure will pass the said valve into a chamber G', thence by a passage h into the chamber H, and therefrom by the pipe or passage M to the cylinder of the ram behind the plunger C², which is thus forced out from the cylinder to effect the breaking of the article placed in position in the apparatus, as hereinbefore described. Upon reversing the movement of the lever L the valve E in the chamber G will be closed by the pressure of the spring K, and the valve F in the other chamber is by the further movement of the lever opened, whereupon the water will be permitted to flow from the ram-cylinder through the pipe M into the chamber H, past the valve F into a chamber F', and therefrom by a pipe or passage i back to the force-pump or reservoir from which the pump is supplied, while at the same time water under pressure will pass by a pipe or passage k from the chamber E to the ram-cylinder to effect the return of the plunger into the cylinder.

Means may be provided to prevent the ram

from turning axially in the cylinder and insure the projection B² on the head of the plunger always being at the proper position to act on the article.

Although we have described a suitable arrangement of valves for regulating the supply of pressure to the hydraulic ram, we do not restrict ourselves thereto, as various other arrangements may be provided for the purpose; neither do we restrict ourselves to the precise construction of apparatus described and illustrated, as variation may be made therein without departing from our invention.

We claim as our invention—

In apparatus for breaking metal rails, &c., the combination of stationary projections, arranged at a distance apart, to receive the pressure of the article while being broken, a hydraulic ram arranged in front of and between said stationary projections, a valved box containing two chambers, one of the said chambers having a passage connecting it with the source of pressure, and a second passage leading from said chamber to the hydraulic cylinder in front of the plunger and forming a constant communication between the source of pressure and the cylinder in front of the plunger, the other chamber being in communication with the cylinder of the hydraulic ram behind the plunger, a valve in each of the said chambers, a spring or springs for normally retaining the valves closed, a lever or equivalent means for operating the valves alternately so as to cause the plunger of the ram to be moved alternately in opposite directions, substantially as and for the purpose hereinbefore described.

In testimony whereof we have signed our names to this specification in the presence of two subscribing witnesses.

THOS. W. WARD.
H. W. LASH.
